PUMP

Glen G. Montgomery and David E. Montgomery,
Mirando City, Tex.

Application February 9, 1937, Serial No. 124,908

1 Claim. (Cl. 103—155)

This invention appertains to new and useful improvements in pumps especially adapted for use in oil wells.

The principal object of the present invention is to provide an oil well pump constructed in such a manner as to save considerable time when the same has to be pulled from the well for the purpose of changing cups and repairing or replacing other parts.

10 Another important object of the invention is to provide a pump which will be positive acting and not susceptible to the ready development of defects.

These and various other important objects 15 and advantages of the invention will become apparent to the reader of the following specification.

In the drawings:—

Figure 1 represents a side elevational view of 20 the pump assembly.

Figure 2 is a longitudinal sectional view through the pump assembly.

Figure 3 is a cross section on the line 3—3 of 25 Figure 2.

Figure 4 is a cross sectional view on the line 4—4 of Figure 2.

Figure 5 is a side elevational view of the ball 30 cage.

Figure 6 is a top plan view of a modified form 35 of the cage.

Figure 7 is a vertical sectional view on the line 7—7 of Figure 6.

Referring to the drawings wherein like numerals designate like parts, it can be seen that 35 the numeral 5 represents the well tubing and numeral 6 generally refers to the pump assembly. This pump assembly consists of the shell 7 having the plug 8 in the upper end thereof from which rises the rod connecting nipple 9.

40 Located within the shell 7 is the barrel 10 on which the pump cups are located, these cups being divided into the upper group 11 and the lower group 12 between which groups is the annular spacer 13. Spacers 14 are provided between the individual cups and a removable retaining nut 15 is provided on the upper end of the barrel 10 so that the cups can be removed and replaced as desired.

50 The tube 16 is threaded into the bushing 17 which, in turn, is threaded into the pocket 18 of the body 19, the upper end of this tube 16 being threaded as at 20 into the lower end of the barrel 10. It can also be observed that the lower end 55 of the shell 7 is provided with the bushing 21

therein and this is slidable on the said tube 16 with the shell 7.

The body 19 is provided with the depending skirt portion 22 internally threaded to receive the upper reduced threaded portion of the body 5 23, and this skirt portion 22 defines a compartment 24 in which is located the ball cage 25 of upwardly tapering construction, the lower end of which threadedly receives an upward extension 26 of the body 23 and between this extension 10 and the lower portion of the cage the seat 27 is clamped for supporting the ball 28. The sides of this cage 25 are provided with openings 29 and ports 30 extend downwardly through the body 19 from the pocket 18 to communicate with 15 the said chamber 24. The body 19 is provided with an upwardly extending recess 31 therein in which the ball 32 is free to move, this ball being seatable on the seat structure 33 which is clamped between the upper end of the cage 25 20 and the body 19. Discharge ports 34 extend radially from the body 19 to open into the space between the body 19 and the well tubing 5.

The lower portion of the body 23 is provided with cups 35.

A modified form of valve cage is shown in Figure 7 and denoted by reference character 25a, the same being provided with an intermediate threaded portion 25b for engaging into the lower end of the skirt 22 and a depression 25c in its 30 upper end for receiving the valve seat 33. The ports 29a extend substantially vertical to be in the same direction substantially as the intake ports 30.

It can now be seen, that when the shell 7 is 35 pulled upwardly, the chamber 36 is increased, causing a suction through the tube 16, ports 30, chamber 24 and body 23. Thus liquid is drawn into the chamber 24, ports 30, pocket 18, tube 16 and chamber 36. On the down stroke of the 40 shell 7, the capacity of the chamber 36 will, of course, be decreased. The ball 28 will become seated on the seat 27 and the pressure of the liquid in the pump will unseat the ball 32 and allow the liquid to pass outwardly through the 45 discharge port 34 to the space between the pump structure and the well tubing 5.

While the foregoing specification sets forth the invention in specific terms, it is to be understood that numerous changes in the shape, size 50 and materials may be resorted to without departing from the spirit and scope of the invention as claimed hereinafter.

Having described the invention what is claimed as new is:—

A pump comprising a lower body having a bore therethrough and arranged in a well casing against movement relative thereto, packing means on the body engaging the well casing, an upper body having a chamber in the upper end thereof and including a skirt threaded on the lower body to provide a lower chamber arranged between said bodies, said upper body having passages connecting said chambers and provided with a valve recess and discharge ports opening outwardly through the outer face thereof and connecting with the valve recess, a valve cage threaded on the lower body within the lower chamber and having side ports communicating with the lower chamber and an end port, a valve seat for said end port and held against the upper body about the lower end of the recess below said discharge ports, a bell valve for said seat to admit fluid under pressure from the lower chamber

to the recess for escape by way of the discharge ports to the well casing above the lower body, a second valve seat mounted at the upper end of the bore of the lower body by said valve cage, a ball valve in the cage to coact with the second seat, a hollow barrel including a sleeve detachably connected to the upper body and in communication with the first-named chamber, packing on said barrel, a reciprocal shell receiving the barrel with a frictional fit by the packing thereof and providing between the barrel and the upper end thereof a suction chamber, and a guide collar slidable on the sleeve and detachably secured to the lower end of the shell for the closing of the lower end of said shell and to cooperate with the packing of the barrel in guiding the movement of the shell relative to said barrel.
